ELECTRICAL APPARATUS

Donald R. Stapleton and William D. Pilcher,
Loda, Ill.

Application February 13, 1933, Serial No. 656,605

8 Claims. (Cl. 200—142)

This invention relates to certain novel improvements in an electrical apparatus.

An object of this invention is to provide a new and useful combination of an electrical apparatus, which may be a motor, generator, or other apparatus, having an operating circuit, a pair of contacts in the circuit, means urging the contacts out of engagement to open said circuit, and means effective to hold said contacts in engagement against the action of said urging means to close said circuit, said holding means including an element thermally responsive to temperature variations in and disposed in close proximity to said apparatus.

Another object of the invention is to provide the new aforementioned combination in which the thermal element is responsive to temperature variations in and is disposed in close proximity to the field of the motor or generator.

Another object of the invention is to provide a new and improved cut-out.

Other objects will appear hereinafter.

The invention consists in the novel combination and arrangement of parts to be hereinafter described and claimed.

The invention will be best understood by reference to the accompanying drawing, showing the preferred form of construction and in which:

Fig. 1 is an elevational view of a conventional electrical apparatus in the form of a motor and illustrating the new combination including the circuit contact;

Fig. 2 is a fragmentary vertical sectional view showing the cut-out applied to a motor;

Fig. 3 is a perspective detail view of the cut-out;

Fig. 4 is a vertical sectional view of the same on line 4—4 in Fig. 3;

Fig. 5 is a horizontal sectional view of the cut-out on line 5—5 in Fig. 4; and

Fig. 6 is a diagrammatic view showing the circuit embodying the new combination.

A conventional electrical apparatus, which may be a motor, generator, or other apparatus, is generally indicated at 10 in the drawing and the apparatus shown being specifically a motor having a field 11. A circuit cut-out is indicated generally at 12 and is associated in the new combination with the field 11. The cut-out 12 is mounted upon a supporting member 13 which in turn is mounted upon a portion of the motor or generator casing 14 in close proximity to the apparatus 10 and, more specifically, to the field 11. In the present instance the mounting of the supporting member 13 upon the casing 14 is effected by a bolt 15 that is extended through the member 13 and

threaded into an aperture in the casing 14. The casing 14 includes a shield 30 having an opening 31 arranged to permit access to the circuit cut-out 12. This opening is normally closed by means of a cover 32 fastened to the shield 30 through the medium of screws 33.

Mounted upon the supporting member 13 is a pair of spaced terminals 16 which are connected in series with the operating circuit of the apparatus, or field 11, (Fig. 6) by means of conductors 17. Pivottally attached, as at 18, to each of the terminals 16 is a pair of yieldable conductive jaws 19 and each of these pairs of jaws 19 carries the outer end of a relatively stationary contact 20; the inner ends of these contacts 20 being attached, as at 22, to a non-conductive block or body 21.

Formed in the body 21 is an aperture 23 and slidably mounted in this aperture 23 is a bolt member 24 to the inner end of which is attached a thermally responsive element in the form of a button 25 of low temperature fusing alloy, such, for example, as a bismuth alloy known to fuse at a preselected temperature.

Insulatingly mounted on the bolt member 21, by means of a non-conductive bushing 26, is a movable contact member 27 which normally bridges the relatively stationary contacts 20 to close the operating or field circuit. The movable contact member 27 is urged out of contacting engagement with the relatively stationary contacts 20 by a spring 28 arranged on the bolt member 24. However, spring 28 is normally held under tension and in ineffective position by the coaction of the bolt 24 and thermally responsive fusible button 25 which bears against the inner side of the body 21 and surrounds the inner end of the aperture 23 (Fig. 4).

A spring 29, having one end attached to the bolt 15 and its other end attached to the block 21, normally keeps the block 21 in the position of Fig. 2 and holds the thermal element or fusible button 25 in close proximity to the field 11 of the motor or apparatus 10. However, should the apparatus, that is the field 11 of the motor or generator 10, become overheated, for any reason, either due to electrical disturbances or surges in the field circuit, or to heat generated by the rotative parts, or for any other reason, above the pre-selected fusing point of the button 25, the button 25 will fuse; whereupon the member 24 is freed for movement in the aperture 23 and the tensioned spring 28 becomes effective to urge the bolt member 24 (to the right Fig. 2, to the left, Fig. 4) and the movable contact 27 out of en-

gagement with the relatively stationary contacts 20 to open the operating or field circuit. Thus the movable contact member 27 is urged out of engagement with the relatively stationary contacts 20 and the operating or field circuit of the motor or generator is thus operated so that the motor or generator is stopped and injury to or destruction of the same prevented.

Thus, it will be seen that the circuit cut-out 12 10 may easily be reached for repair purposes by merely removing the cover 32. The pivotal or swingable mounting of the circuit cut-out permits the device to be shifted to a position permitting quick and easy access for repair purposes. 15 In other words, the device is completely available without disassembly of the shield from the frame part 14 or the disconnection of the wiring or other parts of the device.

While we have illustrated and described the 20 preferred form of construction for carrying our invention into effect, this is capable of variation and modification without departing from the spirit of the invention. We, therefore, do not wish to be limited to the precise details of construction set forth, but desire to avail ourselves of such variations and modifications as come within the scope of the appended claims.

Having thus described our invention what we 30 claim as new and desire to protect by Letters Patent is:

1. A cut-out for dynamo-electric machines, comprising a supporting block shaped to be fastened to the dynamo-electric machine in close proximity to its field, a pair of spaced terminals 35 swingably connected with said supporting block and comprising a part of the circuit for the dynamo-electric machine, a terminal supporting block, a pair of spaced terminal members carried by said terminal supporting block and arranged in electrical contact with said first-named pair of spaced terminals, a bridge element electrically connecting said terminal members, to close the circuit through the dynamo-electric machine, spring means urging said bridge element out of contact with said terminal members, to break the circuit for the dynamo-electric machine, and fusible means resisting movement of the bridge element away from said terminal members and having a portion arranged in operative relation with the field of the dynamo-electric machine, to be fused by excessive heat generated in the environment of said field, to release said bridge element and break the circuit for the dynamo-electric machine.

2. A cut-out for dynamo-electric machines, comprising a supporting block shaped to be fastened to the dynamo-electric machine in close proximity to its field, a pair of spaced terminals swingably connected with said supporting block 60 and comprising a part of the circuit for the dynamo-electric machine, a terminal supporting block, a pair of spaced terminal members carried by said terminal supporting block and arranged in electrical contact with said first-named pair of spaced terminals, a bridge element electrically connecting said terminal members, to close the circuit through the dynamo-electric machine, spring means urging said bridge element out of contact with said terminal members, to break the circuit for the dynamo-electric machine, fusible means resisting movement of the bridge element away from said terminal members and having a portion arranged in operative relation with the field of the dynamo-electric machine, to be fused by excessive heat generated

in said field, to release said bridge element and break the circuit for the dynamo-electric machine, and a spring urging said fusible means in the direction of said field.

3. A cut-out for dynamo-electric machines, 5 comprising a supporting block shaped to be fastened to the dynamo-electric machine in close proximity to its field, a pair of spaced lugs fastened to said supporting block, a terminal pivotally connected with each of said lugs and comprising a part of the circuit for the dynamo-electric machine, a terminal supporting block, a pair of spaced terminal members carried by said block and arranged in electrical contact with said first-named terminals, a bridge element electrically connecting said terminal members, to close the circuit through the dynamo-electric machine, spring means urging said bridge element out of contact with said terminal members, to break the circuit for the dynamo-electric machine, and 10 fusible means resisting movement of the bridge element away from said terminal members and having a portion arranged in operative relation with the field of the dynamo-electric machine, to be fused by excessive heat generated in the environment of said field, to release said bridge element and break the circuit for the dynamo-electric machine, 15 spring means urging said fusible means in the direction of said field.

4. In a dynamo-electric machine, a block of 30 insulating material shaped to be fastened to the dynamo-electric machine in close proximity to its field, a pair of conducting members pivotally connected with said block and comprising a part of the operating circuit for the dynamo-electric 35 machine, a floating block of insulating material, a pair of contact members secured to the floating block and arranged in electrical contact with said conducting members, a bridge electrically connecting said contact members, a bolt passing 40 through said floating block and said bridge and having an abutment engaging the bridge, a spring positioned between said floating block and the bridge to urge the latter out of electrical contact with said contact members, and a fusible 45 element connected with said bolt and arranged in close relation to said field and resisting movement of the bridge away from said contact members, said fusible element fusing at a predetermined temperature, to permit said spring to 50 move the bridge out of contact with said contact members and break the circuit for the dynamo-electric machine.

5. In a dynamo-electric machine, a block of insulating material shaped to be fastened to the 55 dynamo-electric machine in close proximity to its field, a pair of conducting members pivotally connected with said block and comprising a part of the operating circuit for the dynamo-electric machine, a floating block of insulating material, 60 a pair of contact members secured to the floating block and arranged in electrical contact with said conducting members, a bridge electrically connecting said contact members, a bolt passing through said floating block and said bridge and having an abutment engaging the bridge, a spring positioned between said floating block and the bridge to urge the latter out of electrical contact with said contact members, a fusible element connected with said bolt and arranged in 65 close relation to said field and resisting movement of the bridge away from said contact members, said fusible element fusing at a predetermined temperature, to permit said spring to 70 move the bridge out of contact with said contact members and break the circuit for the dynamo-electric machine.

members and break the circuit for the dynamo-electric machine, and a spring connecting said blocks of insulating material with said floating block, to urge the latter in the direction of said field.

5 6. A cut-out for dynamo-electric machines, comprising a U-shaped member having the ends of its legs arranged to be movably connected with the dynamo-electric machine in close proximity to its field, said member comprising a part of the circuit for the dynamo-electric machine, a fusible element carried by said member and arranged in operative relation with the field of the dynamo-electric machine, means comprising a 10 part of said member rendered operable when said fusible element is fused, to break the circuit through the dynamo-electric machine, and means for moving the cut-out bodily and yieldingly holding the same in operative relation with the field.

15 7. A cut-out for dynamo-electric machines, comprising a member arranged to be pivotally connected with the dynamo-electric machine in close proximity to its field, said member com-

prising a part of the circuit for the dynamo-electric machine, a fusible element carried by said member and arranged in operative relation with the field of the dynamo-electric machine, spring means rendered operable when said fusible element is fused, to break the circuit through the dynamo-electric machine, and means for moving the cut-out bodily and yieldingly holding the same in operative relation with the field.

8. A cut-out for dynamo-electric machines, 10 comprising a member arranged to be swingably connected with the dynamo-electric machine in close proximity to its field, said member comprising a part of the circuit for the dynamo-electric machine, a fusible element carried by said member and arranged in operative relation with the field of the dynamo-electric machine, spring means rendered operable when said fusible element is fused, to break the circuit through the dynamo-electric machine, and means for moving 15 the cut-out bodily and yieldingly holding the same in operative relation with the field.
